ROTATABLE HAIR-TREATING IMPLEMENT

Nathan G. Finkelstein, New York, N. Y.

Application December 2, 1947, Serial No. 789,207

7 Claims. (Cl. 132—88)

1

This invention relates to improvements in hair-treating implements for accentuating or restoring waves in growing hair or hair assembled in strands and curls in the ends of hair assembled in strands, such as wigs. It is well known that waves and/or curls in hair are either natural or are induced by winding the strands upon suitable supports or by the application of heat by suitable means or by treatment with chemicals, or combinations of the above means.

It is also well recognized that no comb or brush when operated by a translatory motion longitudinally of the strands will of itself induce or accentuate waves and curls but upon the contrary will straighten the hair when treated by such translatory longitudinal movement alone.

One of the objects of the invention is to provide a hair-treating implement adapted to be so manipulated as to provide a combined translatory and rotative movement which when passed through the hair or strands of hair will enable the residual elasticity of the hair to induce or restore waves therein and curls at the ends thereof.

Another object of the invention is to provide a device of this character having a handle so constructed as to be comfortably grasped and readily manipulated to produce a combined longitudinal and rotative movement as it is passed longitudinally in the strand of hair to accomplish the purpose above described.

Another object of the invention is to provide a hair-treating implement of the character described in which the hair-engaging elements can be rigidly assembled radially and preferably symmetrically with respect to the axis of the handle.

A further object of the invention is to provide a construction in which the hair-engaging elements can be readily and detachably assembled upon the handle.

These and other objects and features of the invention will more fully appear from the following description and the accompanying drawings and will be particularly pointed out in the claims.

Preferred embodiments of the invention are illustrated in the drawings, in which,

Fig. 1 is a view of a rotatable comb;

Fig. 2 is a view of the end of the head of the comb shown in Fig. 3 and showing six hair-engaging combs radially assembled with respect to the extended longitudinal axis of the comb handle;

Fig. 3 is a vertical sectional view of the comb illustrated in Fig. 1 showing a modified form of cap on the end of the shank, a portion of the handle being broken away;

2

Fig. 4 is a vertical sectional view on line 4—4 Fig. 1;

Fig. 5 is a view of a comb embodying the invention in which one or more brushes are radially interposed between adjacent radially disposed combs; and,

Fig. 6 is a vertical sectional view on line 6—6 Fig. 5 showing three radially extending brushes interposed between successive radially extending combs.

The invention as embodied in Figs. 1—4 inclusive comprises a series of six combs assembled radially with respect to the axis of the handle of the comb with means detachably clamping the combs in assembled position upon the handle, but it will be understood that any suitable number of combs or brushes may be thus assembled and clamped together and to the handle in axial relation thereto, the handle preferably comprising flat faces corresponding in number to the number of hair-engaging elements of the hair-treating elements.

As illustrated in Figs. 1 to 5 inclusive each of the combs comprises a back 1 with radial parallel comb teeth 2. The back of each comb has symmetrically converging flat faces 3 and 4 adapted when assembled to position the combs radially with respect to the axis of the handle. Each of the combs is provided at its outer end with a large substantially triangular tooth 5 and at its inner end with another enlarged tooth 6 and having a preferably converging extension 7 adapted to enter and fit a socket 8 in the end portion of a handle 9, as illustrated in Fig. 3. The combs preferably, but not necessarily, are of thermoplastic material and means are provided for detachably clamping the combs in assembled position upon the handle.

Any suitable means may be provided for thus clamping the combs in assembled position. In the constructions illustrated herein the clamping means comprises a star shaped head cap 10 having an annular rabbet 11 adapted to engage a complementary recess in the end teeth 5 of the combs as illustrated in Fig. 1, or a groove 12 adapted to engage a complementary rib 13 in the back of each end tooth 5, as illustrated in Fig. 3. The head cap 10 has extending axially from the center thereof a long shank 14 which may be integral with the cap 10, as illustrated in Fig. 1, or in the form of a long bolt 15 having a head 16 embedded in the head cap 10, as shown in Fig. 3. The shank 14 or 15 is provided with a screw threaded end portion 17 adapted to engage complementary screw threads in an extension of the

recess 8 in the handle or preferably a nut 18 fitting in said extension.

By reason of this construction all of the combs or other hair-treating elements may be assembled in radial arrangement with respect to the axis of the shank with the rabbeted portion of the cap in Fig. 1 engaging the complementary recess in the end of the teeth 5 as shown in Fig. 1, or the rib 13 on the back of each tooth 5 occupying the groove 12 in the cap 10 as shown in Fig. 3. Each of the extensions of the back of the comb may then be drawn together and inserted in the socket 8 of the handle and upon rotation of the handle in the proper direction the extension drawn into the socket 8 of the handle and the effective length of the shank shortened in such manner as to clamp the backs of the comb firmly together and the combs firmly upon the handle.

By reason of this construction the combs can be initially rigidly and readily assembled and upon breakage or damage to any of the combs the same can be readily removed and replaced by unscrewing the handle, substituting a new comb and again screwing up the handle.

The construction disclosed in Figs. 5 and 6 comprises combs similar to those above described but alternating with brushes 19 embedded at their inner ends in backs 23 having converging faces and clamped to the handle in the manner above described. In such modified form any suitable number of brushes and combs may thus be inserted radially between successive combs.

The teeth of the combs may of course be of any desired length in accordance with the character or quality of the hair being treated, and of any suitable material, thermoplastic material being preferably employed. Brushes of any desirable degree of fineness may be used.

In operation the operator will grasp the handle of the implement, force at least two of the hair-engaging elements into engagement with a strand of hair and move the instrument with a translatory motion lengthwise of the hair toward the end thereof and simultaneously impart a rotative motion to the implement which will cause two or more of the hair-treating elements successively to engage the hair and simultaneously and progressively bend the hair with an arcuate movement transversely of the translatory movement and so progressively to bend the hair as to enable the resilient elasticity of the hairs to restore natural waves therein or to induce such waves therein and to produce curls at the ends of the strands of hair.

It will be apparent that the particular embodiment of the invention shown and described herein is of an illustrative character and that various modifications in construction and arrangement of parts may be made within the spirit and scope of the following claims.

Having thus described the invention, what is claimed as new and desired to be secured by Letters Patent is:

1. A rotatable hair-treating implement comprising a head cap having a long shank extending perpendicularly from the center thereof, a circular series of hair-manipulating members having backs provided with side faces symmetrically converging toward said shank, and hair-engaging elements extending radially relatively thereto, said backs being provided with converging extensions, a handle having a socket embracing said extensions and complementary screw

threads in said handle and on said shank adapted to clamp the hair-manipulating members firmly together in radial arrangement upon said shank.

2. A rotatable hair-treating implement comprising a head cap having a long shank extending axially from the center thereof provided at its end with a screw threaded portion, said head cap having an annular recess concentric therewith, a handle member having a socket extending inwardly from the end thereof and provided with an internally screw threaded bore for receiving the screw threaded end portion of the shank, a series of hair-treating elements extending radially of the shank, each having a rigid back provided with flat faces symmetrically converging toward said shank adapted when assembled radially upon the shank to engage like sides of the backs of contiguous radially extending members, each of said hair-treating members having at one end means interengaging the recess in the head cap and at its other end an extension fitting within the socket in said handle with the backs of the hair-treating members clamped together and against the head cap by the rotative engagement of the complementary screw threads of the shank and handle.

3. A translatory and rotatably movable hair-treating implement comprising a handle having at one end an axial inwardly tapering socket, a long straight shank having a screw threaded end portion anchored in said handle, and extending axially through a predetermined distance beyond said socket, a circular series of straight hair-manipulating elements of uniform length and width each having a back extending lengthwise of said shank and provided with faces symmetrically converging toward said shank engaging respectively like contiguous faces of the backs of adjacent elements thereby to position the respective hair-treating elements in symmetrical radial relation to said shank, each of said elements having an extension fitting into the socket in the handle, and a cap on the remote end of said shank operable upon securing the shank into the handle to clamp the hair-treating elements firmly in assembled position.

4. A hair-treating implement as defined in claim 3, in which the hair-treating elements are replaceably secured to the handle in assembled position by the screw threaded connection of the shank to the handle.

5. A hair-treating implement as defined in claim 4, in which the hair-treating elements are all in the form of combs having teeth of equal radial length.

6. A hair-treating implement as defined in claim 4, in which the hair-treating elements include combs having teeth of equal radial length and one or more brushes of the same radial length as that of the combs.

7. A hair-treating implement as defined in claim 4, in which the hair-treating elements comprise alternating combs and brushes of said uniform radial length.

NATHAN G. FINKELSTEIN.
